Philco Radio and Television Corporation, Phila-
delphia, Pa., a corporation of Delaware

Application September 9, 1937, Serial No. 163,131

14 Claims. (Cl. 172—239)

This invention relates to automatic and remote control positioning devices such as may be employed to adjust the position of a tuning element or elements of a radio receiver.

5 The principal object of the invention is to provide a novel device which is capable of controlling the adjustment of the shaft of the tuning element to stop it accurately in a desired position in response to a simple manual action such as the 10 operation of a selected push-button. By the preferred form of the present invention there is provided an apparatus which in response to such a simple manual effort, first adjusts the controlled element to an approximate position within 15 in a selected range or zone and then automatically adjusts the said element accurately to a desired position within said range.

This apparatus comprises two positioning devices, one adapted to effect the approximate adjustment and the other adapted to effect the accurate adjustment of the controlled element. Each of these devices controls the effectiveness of the motive means to drive the controlled element. Each of said devices may comprise a plurality of 25 stop elements, those of one device corresponding to various position zones of the controlled element and those of the other device corresponding to particular positions within said zones. Means, which may conveniently consist of a plurality of selector switches in cooperation with an 30 electrically-operable switch, is provided to render the first device effective to control a motor through a selected contact element and, at the same time, to effect energization of the motor, 35 until the controlled element arrives at its approximate position, when the electrically-operable switch is actuated to render the first device ineffective and to render the other device effective to control the motor.

40 The invention may be more clearly understood by reference to the accompanying drawings, in which

Fig. 1 is a perspective view of one form of the apparatus with certain parts broken away for clarity of illustration;

Fig. 2 is a detail view of one of the selective push-button switches;

Fig. 3 is a schematic illustration of the electrical connections of the apparatus;

50 Fig. 4 is a graphic illustration of the manner in which the apparatus operates; and

Fig. 5 is a fragmentary sectional view illustrating the adjustable mounting of one of the control elements.

55 Referring to Fig. 1, there is illustrated an appa-

ratus for controlling the adjustable condenser elements 1 of a radio receiver. A coarse adjustment device 2 and a fine adjustment device 3 are each adapted to control the positioning of said elements. Both of the devices 2 and 3 are commutators and are used to direct the flow of current in the circuit as will be described in more detail hereinafter. In the specific illustration, the radio receiver tuning elements 1 and the rotor of device 2 are mounted on shaft 4 which 10 is geared to shaft 5 by reduction gearing 6, 7. The rotor of device 3 is mounted on shaft 5 which is driven by motor 8 and in turn drives shaft 4. Thus, the rotors of the devices 2 and 3 are rotatable with the shaft 4, and the position of the rotor of device 3 is correlated with the position of shaft 4.

The device 2, as illustrated, comprises a disk 9 of insulating material, such as Bakelite, mounted on shaft 4 and carrying a pair of arcuate conductive segments 10 and 11 and also a conductive segment 12 which may take the form of a ring with extensions 13 spaced from the segments 10 and 11. Electrical connection is made to segment 10 by means of the slip ring 14 which is electrically connected to segment 10, and likewise electrical connection is made to segment 11 by means of slip ring 15 which is connected to segment 11. The brushes 16 and 17 carried by a stator plate 18 engage or wipe over the slip rings 14 and 15, respectively. A third brush 19 also carried by the stator plate engages the ring segment 12. A plurality of brush-like contact elements 20 are adjustably mounted in a slot 21 in the stator plate, although the elements 20 may be permanently fixed in position. These contact elements engage the conductive segments 10 and 11 and also the extensions 13 of segment 12 during rotation of the rotor, as will be described further hereinafter. Each of the contact elements 20 represents a particular range or zone of movement of the tuning elements 1.

The device 3, as illustrated, may comprise a rotatable drum 22 having arcuate conductive segments 23 and 24 separated by opposed insulating segments 25 (only one is shown). An end plate 26 of insulating material carries slip rings 27 and 28 which are connected, respectively, to the conductive segments 23 and 24. Brushes 29 and 30, carried by the housing 31, engage and wipe over the slip rings 27 and 28, respectively. A plurality of brush-like contact elements 32, corresponding in nature to the contact elements 20, are adjustably carried in slots 33 in the housing 31. Each

of the contact elements 32 effectively corresponds to a particular position of tuning elements 1.

The rotor of device 2 has been illustrated as being a rotatable disk, and the rotor of device 3 has been illustrated as being a rotatable drum, merely for the sake of illustration. Either of these devices may take either of these forms or any other form by which the necessary switching or commutation may be obtained, as set forth hereinafter.

The apparatus comprises further a multiple-pole, double-throw switching device 34, which device comprises a row of stationary contacts 35, a second row of stationary contacts 36, and movable contact fingers 37 carried by a movable shaft or rod 38 and adapted to engage either row of stationary contacts, the fingers 37 being insulated from one another. The rod 38 is connected to an armature 39 which is actuated by either of the solenoids 40 and 41.

A plurality of selective manuals or push-button selector switches, designated generally 42, are provided, one for each position to which it may be desired to adjust the tuning element 1. Each of these switches (see Fig. 2) may comprise spring finger contacts 43, 44 and 45 mounted on a common insulating support 46, and a push-button 47 which is adapted to engage the finger 43 and thus to cause the three contacts to engage one another. A latch 48 is provided for each switch, the row of latches being mounted for joint rotary movement on a rotatable rod 49. When one of the push-buttons is pressed inward, it causes finger 43 to engage finger 44 and causes finger 44 to engage finger 45, and at the same time the push-button actuates the latch 48, releasing any previously depressed push-button. When the actuated push-button is released, the finger 44 is permitted to move away from finger 45 but the button is latched in and maintains the contact between fingers 43 and 44. Thus the contact between fingers 44 and 45 is temporary and persists only as long as the push-button is held in, but the contact between fingers 43 and 44 is maintained by the latching in of the button. When another push-button is pressed inward, any other push-button which is in latched position is released by the actuation of the latch mechanism. The purpose of this will be apparent later.

The electrical connections of the apparatus, although shown in Fig. 1, are more clearly shown in the diagram of Fig. 3, and the operation of the device will be described presently with reference to that figure. A source of electrical energy, shown as a battery 50, is provided for energizing the motor 8 and the solenoids 40 and 41. A lamp 51 having a high impedance compared to the impedance of motor 8, is included in the motor circuit, and a short-circuiting switch 52 is shunted across the lamp, for a purpose to be described later.

Referring now to Fig. 3, wherein for simplicity the devices 2 and 3 are schematically illustrated as disks or drums with the elements 20 and 32 engaging their peripheries, normally switch 52 will be closed and the motor 8 and solenoids 40 and 41 de-energized, the armature 39 being within solenoid 40 so that switch elements 37 are in contact with switch elements 36. Suppose now that a push-button selector switch X corresponding to a desired broadcasting station is pressed inward, momentarily closing all three of its contact fingers 43, 44 and 45. It will be seen that this closes the circuit 53 energizing the solenoid

41. The switch 34 is thus thrown to the left, as viewed in the figure, closing at contacts 35. The releasing of the selector push-button disengages contact finger 45 but the fingers 43 and 44 are held in engagement by the latch mechanism 5 above described.

The closing of switch 34 closes the motor circuit as follows:—from the battery 50 through switch 52, the motor armature, the motor field winding 54, switch 34, conductor 55, segment 10 10 of device 2, conductor 56, switch 34, conductor 57, contacts 43 and 44, and conductor 58 back to the battery. The motor rotates shaft 5 clockwise, thus rotating the rotor of device 2 counterclockwise until the contact element to which 15 conductor 56 is connected leaves the segment 10 and interrupts the motor circuit. The said contact element, however, engages segment 12 of device 2 and thus energizes the solenoid 40, as will be apparent, causing the switch 34 to throw 20 to the right. The motor is then energized as follows: from battery 50 through the motor 8 (field winding 54), switch 34, conductor 59, segment 24 of device 3, the contact element 32 corresponding to the above-mentioned contact ele- 25 ment of device 2, conductor 60, switch 34, contacts 43 and 44, and conductor 58 back to the battery. The motor 8 again rotates shaft 5 clockwise until the contact element to which conductor 60 is connected leaves segment 24 and en- 30 gages the insulating segment 25, thus interrupting the motor circuit. Due to the reduction gearing between shafts 4 and 5, the rotor of device 2 is rotated only a slight amount by the operation of device 3. For example, if the gear reduction is 16 to 1, the maximum possible rotation (180 degrees) of the rotor of device 3 during the fine adjustment operation will rotate the rotor of device 2 only about 11 degrees.

Thus the tuning elements 1 are adjusted to 40 an approximate position within a certain zone by the action of device 2, and the tuning elements are then adjusted to an exact position in that zone by the device 3. To adjust the tuning elements to any other desired station it is simply necessary to press another push-button corresponding to that station.

As may be seen from Fig. 3, one end of the field winding is connectible through switch 34 to segment 10 of device 2, whereas the other end 50 is connectible to segment 11. One of these two segments will be energized by contact with the element 20 and will cause the motor to rotate in such a direction as to cause the top of segment 12 to move towards the energized contact ele- 55 ment 20. Likewise, when the second rotor is in use, the two ends of the field winding are connected to segments 23 and 24 of the device 3 and one of these segments will be energized by the contact element 32, causing the motor to ro- 60 late in such a direction as to make the top of insulated segment 25 rotate towards the energized contact element 32. Hence, when the push-button is depressed, the motor will cause the tuning element to rotate towards the desired 65 position. This rotation may be carried by means of the approximate control 2 to the approximate tuning position, at which point rotor 2 will relinquish control. This may occur either just before or just after the desired position is reached. 70 In any event, the fine control 3 will then cause the motor to rotate the device directly to the desired position. The operation thus effected is as above described. The direction of rotation of motor 8 in any instance will depend upon the 75

positions of the rotors of devices 2 and 3 which determine which field winding of the motor 8 will be energized. It will be obvious that any number of push-buttons and associated contact elements 20 and 32 may be provided within the bounds of practicability and the mechanical limitations of the particular apparatus. Moreover, the contact elements and associated circuits cannot interfere with one another, since the circuit of only one contact element will be energized at one time.

The operation of the device may be more clearly understood from the following explanation with reference to Fig. 4. Suppose that the tuning element 1 may be adjusted through 180° and that it is desired to adjust the tuning element to any one of six positions within this range. Referring to Fig. 4, these six positions, which may correspond to six different broadcasting stations, are indicated by the lines A, B, C, etc. The device 3 is adapted to adjust the tuning element 1 accurately to the desired position provided, however, that the tuning element is first brought approximately to the desired position. As will be apparent, the device 3 can control the tuning element 1 only through an angular displacement corresponding to the angular size of the segments 23 and 24 divided by the gear ratio between the device 3 and the tuning elements 1, and the accuracy with which the device 3 will adjust the positioning of the tuning element 1 is similarly determined by the arcuate width of the segment 25 and the gear ratio. If, for example, the segments 23 and 24 each extends for about 176° and the gear ratio (6—7) is 16 to 1, then the device 3 will bring the tuning element to the desired position from any position within the range 11° on either side of the desired position. In Fig. 4, this range is shown as zone a corresponding to position A, zone b corresponding to position B, etc. In other words, the angular size of the segments of 3 and the gear ratio determine a zone or position range within which the tuning element must first be adjusted by the device 2. The several zones may overlap or may not meet. In either case, one zone will not interfere with another.

The device 2 will adjust the tuning element to a position determined by the angular displacement between the segments 10 and 11, and the contacts 20 should be adjusted so that this region is entirely within the zone corresponding to the station which it is desired to receive. For example, in Fig. 4 the region g indicated by the double arrow lines, indicates the region within which the device 2 will first adjust the tuning element and then the device 3 will complete the tuning or adjusting operation. It is necessary that the region, for example region g, be entirely within the zone, for example zone a, over which the device 3 has control. The region, however, may be anywhere within the zone, as for example, the region h is on one side of position B but still within zone b. Where two stations have overlapping zones, as for example, stations E and F, and where the region corresponding to an element 20 of device 2 can be positioned entirely within both zones, then a single element 20 may be used with both elements 32 to cause adjustment of the device to either E or F depending upon which of the elements 32 is employed.

Thus, it will be apparent that the device 3 will control the adjustment of the tuning ele-

ment 1, provided it is first brought within the zone over which the device 3 has control, and that the device 2 serves to first adjust the tuning element 1 to a position within that zone after which the device 3 takes control to complete the final adjustment.

As indicated above, it is not necessary that there be a contact element 20 corresponding to each contact element 32. It is, however, necessary that there be a section of switch 42 and of switch 34 and a contact element 32 for each station that it is desired to tune. For example, the several contact elements 20 may be permanently fixed so as to divide the tuning range into a number of fixed regions. Several stations within any one region may be automatically tuned in by providing a contact element 32 for each desired station. Each of these different elements 32 would then cooperate with the same element 20 to effect the desired tuning. In this instance, each element 32 would be connected to a different section of switch 34 but the same element 20 would be connected to each of these several switch sections. This arrangement is shown in Fig. 3 by contact 20a which is connected to operate with either contact 32a or 32b to tune in a station corresponding to either 32a or 32b, both stations being located in the region of contact 20a.

It will further be apparent that it is unnecessary to use the manual push-button station selector means shown but that, if desired, an automatic time-controlled mechanism may be used to effect the switching operation herein illustrated as performed by the several selective manuals 42. Such mechanisms are well known and are to be considered the equivalent in circuit operation of the push-buttons 42.

In practice, it may be desirable to mount the device 3 on the tuning element 1 which is often resiliently mounted. In this case, the device 2 may be separately mounted and connected to 1 through a flexible coupling. While the contact elements 20 and 32 may be adjustably mounted in any suitable manner, there is shown in Fig. 5 one form of adjustable mounting wherein the insulating plate 61, corresponding to either the stator plate 18 or the housing 31, carries an adjustable sleeve 62 within which a spring-pressed brush 63 is disposed, the brush engaging surface 64 corresponding to the rotor surface of either device 2 or device 3. The adjustment screw 65 also serves to hold the terminal 66 to which electrical connection is made.

The principal purpose of lamp 51 is to enable the manual adjustment of contact elements 20 and 32 without causing undesired operation of the apparatus. When the switch 52 is opened, the high impedance of the lamp is inserted in the motor circuit and prevents operation of the motor. With the radio receiver tuned manually to a certain station, the apparatus may then be adjusted as follows: The push-button to be used for that station is pressed, causing switch 34 to throw to the left as above described. The contact element 20 associated with the particular push-button is then moved until the lamp is extinguished and the switch 34 throws to the right. The contact element 32 associated with the particular push-button is then moved until the lamp is again extinguished. This process is repeated for each of the push-buttons and the associated contact elements, it being understood, of course, that the radio receiver will be tuned.

manually to each desired station before the adjustments are made.

It will be apparent that the invention is capable of various modes of expression and is applicable to various usages. It is not, therefore, to be limited by the disclosure herein contained.

I claim:

1. In an apparatus for positioning a movable element, a motor for moving said element, a positioning device comprising a plurality of contact segments engageable by a contact element, a circuit including one of said contact segments and said contact element for controlling the energization of said motor to move said movable element to a selected position range or zone, a second positioning device for controlling the energization of said motor to move said movable element to a desired position within said range, means for connecting either of said devices to said motor to the exclusion of the other device, manually operable means for actuating said connecting means to connect said first device to said motor, and a circuit including another of said contact segments and said contact element for actuating said connecting means to connect said second device to said motor when said movable element has been moved to a position within said range.

2. In a control apparatus for positioning an element, such as a radio tuning element, having a rotatable shaft, a motor for rotating said shaft, a first positioning commutator constructed and arranged to rotate in correlation with said shaft, a second positioning commutator geared to said shaft and arranged to have greater angular displacement than said first positioning device, a plurality of segments on each commutator, a contact for each commutator engageable with said segments, two circuits through said motor for causing said motor to rotate in either direction, a switch for connecting segments of one or the other of said commutators in circuit with said two motor circuits, and an additional circuit on said first commutator for operating said switch to disconnect said first commutator and connect said second commutator to said two motor circuits when said shaft is rotated to a selected position.

3. In a control apparatus for positioning a movable element, a first positioning device for controlling the movement of said element to a selected position range or zone, a second positioning device for controlling the movement of said element to a desired position within said range, a linkage between said second positioning device and said element for correlating the position of the former with respect to the latter, a selective manual, and switching means controlled by said selective manual and said first device for rendering said devices effective successively to control the movement of said element.

4. In a control apparatus for positioning a rotatable shaft, a motor for rotating said shaft, a first positioning device for controlling the rotation of said shaft to a selected position range or zone, said positioning device comprising a rotor carrying spaced contacts and a plurality of contact elements engaging said rotor contacts, said rotor being rotatable by said shaft, a second positioning device for controlling the rotation of said shaft to a desired position within said selected range, said second positioning device comprising a rotor carrying spaced contacts and a plurality of contact elements engaging said rotor contacts

and each corresponding to a desired position within a position range or zone, a linkage between said second positioning device and said shaft for correlating the position of the former with respect to the latter, means for connecting either of said devices to said motor to the exclusion of the other device, selector means for energizing said motor and for actuating said connecting means to render said first device effective to control the rotation of said shaft, and means for subsequently actuating said connecting means to render said first positioning device ineffective and to render said second positioning device effective to control the rotation of said shaft.

5. In a control apparatus for positioning an element such as a radio tuning element having a rotatable shaft, a motor for rotating said shaft, a first positioning device rotatable with said shaft for controlling the rotation of said shaft to a selected position range or zone, a second positioning device rotatable with said shaft for controlling the rotation of said shaft to a desired position within said range, a first circuit including the first positioning device for controlling the energization of said motor to cause rotation of said shaft to said desired position range or zone, a second circuit including said second positioning device for controlling the energization of said motor to cause rotation of said shaft to said desired position, a switch for selectively energizing said circuits and means on said first positioning device for actuating said switch to de-energize said first circuit and to energize said second circuit when said shaft has been rotated to said selected position zone or range.

6. In a control apparatus for positioning a movable element, a reversible motor for moving said element, a commutator having a pair of main conductive segments and an auxiliary conductive segment, at least one contact element adapted to engage said segments, a pair of circuits for said motor connected respectively to said main segments, manually operable means for connecting said contact element in circuit with said motor and an energizing source therefor, whereby said apparatus operates to position said movable element, a circuit connected to said auxiliary segment and to said contact element, and switching means controllable by said last-named circuit for transferring control of said motor to an auxiliary device.

7. In a control apparatus for positioning an element such as a radio tuning element having a rotatable shaft, a motor for rotating said shaft, a first positioning device rotatable with said shaft for controlling the rotation of said shaft to a selected position range or zone, a second positioning device rotatable with said shaft for controlling the rotation of said shaft to a desired position within said range, a first circuit including the first positioning device for controlling the energization of said motor to cause rotation of said shaft to said desired position range or zone, a second circuit including said second positioning device for controlling the energization of said motor to cause rotation of said shaft to said desired position, an electrically operable switch for energizing either of said circuits, a selector switch having momentarily operable contacts for energizing said electrically operable switch in a direction to energize said first circuit, and means on said first positioning device for energizing said electrically operable switch in another direction to deenergize the first circuit and energize the

second circuit when said shaft has been rotated to said selected position zone or range.

8. In a control apparatus for positioning a radio tuning element having a rotatable shaft, a reversible motor for rotating said shaft, an energizing circuit for said motor, a first commutator rotatable with said shaft and comprising a pair of main conductive segments and an intermediate conductive segment, a plurality of contact elements arranged to engage said segments, circuit connections to said segments and said contact elements, a second commutator rotatable with said shaft and comprising a pair of conductive segments, a plurality of contact elements arranged to engage said last-mentioned segments, circuit connections to said segments and said contact elements, electrically-operable switching means constructed and arranged to connect said motor to the pair of segments of either commutator and to connect the motor circuit to the associated contact elements, a plurality of selector switches for completing the circuit of any one of the contact elements, each of said selector switches being constructed and arranged to energize said electrically-operable switching means so as to complete the circuit connections to said first commutator and its associated contact elements, and a circuit completable through the intermediate segment of said first commutator for energizing said electrically-operable switching means so as to complete the circuit connections to said second commutator and its associated contact elements.

9. In a control apparatus for positioning a radio tuning element having a rotatable shaft, a reversible motor for rotating said shaft, an energizing circuit for said motor, a first commutator rotatable with said shaft and comprising a pair of main conductive segments and an intermediate conductive segment, a plurality of contact elements arranged to engage said segments, circuit connections to said segments and said contact elements, a second commutator rotatable with said shaft and comprising a pair of conductive segments, a plurality of contact elements arranged to engage said last-mentioned segments, circuit connections to said segments and said contact elements, an electrically-operable multi-pole double-throw switch arranged to connect said motor to the pair of segments of either commutator and to connect the motor circuit to the associated contact elements, a plurality of selector switches for completing the circuit of any one of the contact elements, each of said selector switches being constructed and arranged to energize said electrically-operable switch in one direction, and a circuit completable through the intermediate segment of said first commutator for energizing said electrically-operable switch in the opposite direction.

10. In a control apparatus for positioning a radio tuning element having a rotatable shaft, a reversible motor for rotating said shaft, an energizing circuit for said motor, a first commutator rotatable with said shaft and comprising a pair of main conductive segments and an intermediate conductive segment, a plurality of contact elements arranged to engage said segments, circuit connections to said segments and said contact elements, a second commutator geared to said shaft so as to rotate to a greater extent than said shaft and comprising a pair of conductive segments, a plurality of adjustable contact elements arranged to engage said last-mentioned segments, circuit connections to said segments and said

contact elements, an electrically-operable multi-pole double-throw switch arranged to connect said motor to the pair of segments of either commutator and to connect the motor circuit to the associated contact elements, a plurality of selector switches for completing the circuit of any one of the contact elements, each of said selector switches being constructed and arranged to energize said electrically-operable switch in one direction, and a circuit completable through the intermediate segment of said first commutator for energizing said electrically-operable switch in the opposite direction.

11. In a control apparatus for positioning a rotatable shaft, a motor for rotating said shaft, a pair of positioning devices each operable by said motor, each of said positioning devices comprising circuit making and breaking elements for controlling the operation of said motor, means for connecting one of said devices to said motor to the exclusion of the other and vice versa, manually operable means for initiating operation of the apparatus and for actuating said connecting means to connect one of said devices to said motor, and means controllable by said one device for actuating said connecting means to connect the other of said devices to said motor.

12. In a control apparatus for positioning a rotatable shaft, a motor for rotating said shaft, a pair of positioning devices each operable by said motor, each of said positioning devices comprising a plurality of contact segments engageable by a contact element for controlling the operation of said motor, the said contact element representing a position of said shaft, means for connecting one of said devices to said motor to the exclusion of the other and vice versa, manually operable means for initiating operation of the apparatus and for actuating said connecting means to connect one of said devices to said motor, and means including a contact segment on said one device for actuating said connecting means to connect the other of said devices to said motor.

13. In a control apparatus for positioning a rotatable shaft, a motor for rotating said shaft, a pair of positioning devices each operable by said motor, each of said positioning devices comprising circuit making and breaking means, including a plurality of contact elements corresponding respectively to positions of said shaft, for controlling the operation of said motor, means for connecting one of said devices to said motor to the exclusion of the other and vice versa, manually operable means for selecting a contact element corresponding to a desired shaft position and for simultaneously actuating said connecting means to connect one of said devices to said motor, and means controllable by said one device for actuating said connecting means to connect the other of said devices to said motor.

14. In a control apparatus for positioning a rotatable shaft, a motor for rotating said shaft, two circuits through said motor for causing said motor to rotate in either direction, a commutator including two main segments and an intermediate segment arranged to rotate in correlation with said shaft, a second commutator comprising two main segments arranged to rotate through a greater angle than said first commutator, a double throw change-over switch, circuits through one side of said switch and the main segments of the first commutator to the two motor circuits; circuits through the other side of said switch and the main segments of said second

commutator to the two motor circuits, an operating mechanism for said switch, a circuit through the intermediate segment of said first commutator for energizing said operating mechanism to operate said change-over switch, to thereby open all circuits of said first commutator

and to close circuits of said second commutator, a manually operable switch, and an auxiliary circuit through said manually operated switch for energizing said operating mechanism to return said change-over switch to normal position. 5

JACKSON H. PRESSLEY.
